CLAIM

The ornamental design for a pivot wheel, as shown and described.

DESCRIPTION

FIG. 1 is a perspective view of a pivot wheel showing the design;

FIG. 2 is a front elevational view of the pivot wheel of FIG. 1;

FIG. 3 is a rear elevational view of the pivot wheel of FIG. 1;

FIG. 4 is a right elevational view of the pivot wheel of FIG. 1;

FIG. 5 is a left elevational view of the pivot wheel of FIG. 1;

FIG. 6 is a top plan view of the pivot wheel of FIG. 1; and, FIG. 7 is a bottom plan view of the pivot wheel of FIG. 1. The dash-dash broken lines in the drawings depict portions of the pivot wheel that form no part of the claimed design. The long dash-dot broken lines in the drawings define the boundaries of the claim and form no part thereof.
